BRASSIÈRE

Gertrude Whitman, Jamaica, N. Y.

Application November 25, 1950, Serial No. 197,627

4 Claims. (Cl. 2—42)

1

This invention relates to a brassière that can be worn with straps or without straps. As a garment for underclothing wear or sports wear, in sport sunback clothes, and bathing suits; as well as in corsets, short and long line brassières.

Among the objects of this invention are to make a reasonably inexpensive brassière, with the minimum of cost, and labor, adaptable to any size, doing the correct job for next to nothing immediately with no middleman needed. By eliminating expensive frame makers. Cutting costs to a fraction in labor and material. A saving in any time not only the present when economy is vital.

Attractive neat bosoms are the desire of most women. In fact, and in fancy. With a correctly groomed woman, she is only so when her bosom is elevated and in proper position. Otherwise dresses fit improperly; the woman herself looks all top and no bottom. Giving an outward appearance of sloppiness, not barring the finest designer's dress creation worn to the fanciest affair. A woman will look as though she is literally ready to lose something any minute.

That is frankly what I am trying to do and have eliminated in my brassière. Believe me, the heavier women, myself included, are sure a mess these days.

The designers surely have created many brassières that defeat the purpose. Namely, a practical, inexpensive job to both cost, durability, wearability and correct fit is a rarity in the brassière business.

To not only the small, average and large, but to the very large.

Why? Merely because fashion comes first, instead of fit. Yes, even the thoroughly unimportant femininity is considered before fit. The idea being a new season. Well, another new brassière.

Preferably designed up by an exclusive man designer, salary in a few figures. That has a man's viewpoint, nonetheless of what a woman needs.

Usually working off a live and figuratively correctly proportioned model. From which the designer worked up the pattern in sizes or down likewise. A complete waste of time for a garment is created for the average figure, that can be easily taken care of with little or no inventiveness.

Leaving the small and large figures to grope like gnomes for the impossible to find a correct bra. Resulting in another brassière bought, worn, perhaps once if that is all, nothing being exchangeable of course, after wearing.

2

Which, of course, can be so easily eliminated. By this little brassière of mine. Each bosom convexity being completely, inexpensively encircled so correct fit is gotten immediately providing a chic, easy to make perfect fitting brassière to have with no effort at all, to wear, and comfortable as a bug in a rug.

Another object is to provide an accessory device of simplicity in construction that can be attached, to the cup of any brassière completely circular in construction. Pocketing and holding the entire bosom, not one bit of flesh protruding from the bust itself because of its all-round encasing.

15 This is done by circles of wire B, encasing the bosoms and dividing them with a soft pliable metal tiny strip of copper S, that holds itself firmly to the chest wall, all owing for a good, simple, practical garment, at cost to women and manufacturer. That does the job and makes women's bosoms look their best and most beautiful. Allowing freedom of movement, comfort supreme, up-lift ideal, health and breathing aided to by proper division allowing to breathe with ease.

20 In the accompanying drawings are shown one or more of various possible embodiments of my invention's features.

Figure 1

Figure 1 is a front view of the frame B. Which consists of two correctly circular sizes wires closed with two interlooped looped edges 1. Covered over by a strip of soft sheet copper S, $\frac{1}{8}$ of an inch high, 2 inches long and rolled over looped edges of wire at the bosom division or separating point. Joining the two circular braces of interlooped wires by a joiner member. That can be made of such soft pliable metal such as sheet copper S or any other pliable metal. The frame B is made of two pieces of circular pliable wires. With interlooped looped edges 1, connected by a bridge member of soft metal such as sheet copper S. This is twisted around looped edges of wire 1, 35 at the bosom's separating point, having complete twisted outer edges 2 of copper. These twisted over edges 2 of sheet copper, are gotten by turning edges in and under tightening same. This is covered by fabric, any kind whatsoever may be used.

40 Cut a complete one-piece circular pattern of lightweight fabric 3, darting the cup on both right and left centers of the cups. Then sewing the fabric 3 on the frame B all the way around the frame. Covering same outer edges of inside of cup pattern with a tunnel of plush 4. Sewing

same down with stitching to form soft pad or soft cushion for inside of the outer edges of one's bosom, so that the brassière feels comfortable to wear.

Referring now to the drawing, the cup is formed by drawing a circle on a piece of fabric. Taking the pattern of a one-piece uncut circular outline. Placing the cloth cup fabric with the bias on top. Then stitching the fabric around the edge of the brace B. Folding the bottom of the cup on the straight. Placing an inclusion or dart for extra support of material on the bottom outer edges of each cup C, folding over and stitching down over the circular braces B. The fabric is folded over brace B, sewing the facing of plush 9 on the outer edge of cup frame by stitching. These edges of fabric extend around wire as a passageway which has been folded over to receive the supporting frame or brace B.

A little bridge 10 connection to hold straps 13, 14 is secured to the top of each cup. On top of which are directly sewn shoulder straps. Right shoulder strap 13, left shoulder strap 14. The right shoulder strap 13 extends over the shoulder crossing from right shoulder over down to engage the left brass ring 15, then extending downward to corset ring 17 in center middle of the back of a woman's corset. Looping through the upper edge of corset ring 17 snapping to its own strap Y. Likewise left shoulder strap 14 extends downward over the shoulder to engage right brass loop 19, passing through same, and extending downward to a third brass ring hooking each to its own strap end Z on the upper end of corset ring 17. On the corset's back center of same.

Strapless.—When worn strapless a single strap X is cut, passing through brass loop 15—to second brass loop 19 on corset's center back through same brass loop 19. The two hanging ends u—v snap over third brass loop 17 to its own snap. The brassière strapless hooks to its right end strap O, left strap end T, snapping in a manner to look like an inverted triangle. The bridges 10 off which straps are cut, are tucked under and inside of cup. Hidden away.

Figure 2

Figure 2 is a back view showing the closing of the brassière and how its worked by means of shoulder straps moving in opposite directions from right to left center back, from left to right center back. A band 16 is secured to outer edge portions of the cups C. That can be any pliable fabric, stitching same down to inside edge of cup of the outside of cup, by any method desired, hand or machine. This band of material 16 terminates in elastic bands 20. That terminates at their ends by silk tape 21 by turning back and over 15—19, two center brass rings of any such pliable metal such as copper. The same on right and left center backs. This same elastic end is bound off after the two brass loops 15—19 are sewn on to same raw edges that turn back and are bound off by silk tape 21.

The brass loops 15—19 acting as a coupling device in conjunction with the shoulder strap and a third brass loop at corset's center back where it anchors the garment. Dividing, uplifting, separating, raising and holding the bosom firm.

The plushing 9 is placed over to give a smooth feel to bosom and sewn down around the inside cup of edges.

Figure 3

Figure 3 is a fragmentary prospective showing the idea as strapless, when wearing strapless cut straps away from bridges 10. Use a single strap X. Passing same strap through brass loop 15, to brass loop 19 through same brass loop. Extending ready to grasp the third brass loop outer edges 17 and snap each to its own strap. The right strap end of strap U snaps over the third brass loop 17 on corset's center back to its own end snapping. The left strap end V snaps over third brass loop 17 to its own end by snapping.

Figure 4

Figure 4 is a transverse sectional view, showing a preferred embodiment, showing a brace B made of looped edges of wire 1. Having a connector of sheet copper S covered by plush L. Wound over brace B, at the copper ends M at bosom's division point, having two perfect circular braces B connected by a piece of any soft metal such as sheet copper S, twisted at its ends around looped ends of brace B. Holding there by tight twisting ends. That is under the fabric plush and hidden.

Figure 4 is a view taken of back transversely showing backs of material secured to the outer edges of each cup. This can be of pliable material it is stitched 18 down on inside of cup. By any method desired. The shaped band of pliable material 16 terminates at its end, in elastic bands 20. That again terminates at its ends by brass loops 15—19. Turning over elastic ends binding off bias with silk tape.

Figure 5

Figure 5 is a fragmentary view showing two locked pieces of interlooped brace B. By cutting away piece of sheet copper showing same.

Figure 6

Figure 6 is a transverse view of back and its closing showing taping of elastic bands back over brass rings 15 and 19 each one respectively silk taped. Anchoring them in position.

Referring now to the drawings, the circular cup illustrated. Folded bias on top and on the straight at bottom forms the cone shape by folding over at the bottom with an inclusive or dart. Is folded over the braces (circular B). Sewn directly to circular frame B the top bias part on top, the straight on the bottom sewing so to give pulling and tension or uplift to cup to afford the desired concavity by stitching. Covering all around with plush for smoothness.

Sewing this neatly on top of fabric by hand covering at the same time copper connection with self-same plush to assure comfort, and softness, minus any pressure.

Attaching two little bridges 10 that can be used with shoulder straps. Or tucked away inside of bosom for strapless wear. By merely cutting straps away. Straps are usable by merely sewing to the bridges. Minus any artifices such as buckles or elastics.

Referring now to the drawings, the circular cup 3 illustrated is sewn over B or braces. These arcuate circular braces of soft pliable wire with interlooped ends, are covered with this soft pliable material any kind can be used. It is formed of a circular piece of fabric 3. Folded on the bias on top for firmness, on the straight at bottom for uplift. Darts 4 off top of each up taken by pulling a small tiny dart in and sewing same with stitching. So likewise darts 6—5 going in-

ward in cups are taken by pulling tiny bit of fabric in, sewing same down.

Left was a large dart on the bottom outside edge of each cup. I folded the material and sewed same to the outer edges of each cup for reinforcement or extra uplift. Folded the fabric over showing the reinforcement on outer edges of cup C.

The fabric is folded over and sewn down to the circular braces B, the end of fabric 3 is sewn around the edges of wire braces B and sewn to and directly on wire B. The end extending around the fabric as a tunnel 9. Covered by a one-piece, ribbon G folded over and sewn down. Which has been folded over to receive a supporting frame or circular brace B. The supporting frame B is made of two circular pieces of wire soft and pliable interlooped at its ends. Joined together by a pliable metal such as copper S. Bent in and curved to chest wall giving division supreme.

Wrapped around tightly looped ends of wire 1, at bosom's separating point. Having a rolled edge piece of copper 2. These are gotten by twisting same around looped ends of wire at 25 bosom's division. A padding of soft plushing 27 covers both copper S connector as well.

A little bridge 10 or strap holder is secured to the top of each cup. The right shoulder strap 13, left shoulder strap 14 being sewn on same 30 inside.

Cutting itself away by a mere snip of scissors the straps are cut off the bridge to wear strapless, a strap is used passing through brass rings 15-19 and center back slipping through and travelling down hanging ready to connect and go through third brass loop 17 on corset center back, snapping each to its own snap of strap by snappers for strapless wear.

Back on again with thread and needle. Its 40 with straps closing through the manner of straps described in Figure 2.

According to the present invention, these two pieces of wire brace B, interlooped at their raw ends by manipulation, minus anything such as soldering or igneous artifices. Connected together at S by a copper piece of stripping, wrapped around looped edges by pliers, at the bosom's division point, shown in Figure 1.

Covered over by a completely circular cup pattern 3 in Figure 1 encompassing the entire bosom taking in all flesh of bosom, all the way around itself cupping the two individual bosoms. Darted on top, bottom and sides. The bottom outer edges have an extra reinforcement of fabric for extra support and uplift. The copper connector S serves as a connector and positioner of bosom giving the firmness and projection needed.

Preferably all metal units are detachable. The two wire pliable braces B arcuate in construction. And their connector copper S small cutting of copper, are preassembled as a unit and attached to the completely circular cups, to serve as the brace thereof and the connector therebetween.

Sewn together by merely stitching over brace B covered over with smooth plush for softness. The guides being the wire itself over which stitching is applied by hand or machine.

Covering for which a nice plush is placed on to give smooth and comfortable feel to bosom. In the preferred back view shown in Figure two is shown a number of very important things all contributing to ultimate wonderful workability

and the practical down-to-earth usability and correct fit this brassière gives.

Shaping a piece of taffeta and securing it to the inside of each bust cup covered wire frame. Doubling this for extra long durable wear, preventing friction of arm wearing out like single sides over and over again, down. Both on right and left backs.

Then through having a straight banded double side. Attached to same likewise on both sides an elastic band 20 two inches wide. Through which are slipped two individual brass loops, 15-19, right and left, center back that were slung through on left and right outer edge on 15 the elastic raw edge. Turning elastic back. Covering same with a silk piece of tape to hold rings firmly in position. That ribbon of shoulder straps can pass through same rings at center back on down and snapping to brass loop 17 attached to the corset back. Snapping each to its own strap ends X and Y over. In the transverse sectional, Figure 3, view showing the idea as strapless. The tiny bridge 10 folding, can be tucked into cup. Hidden entirely from view. A strap X is passed through two center back loops 15 and 19 very easily used. By slipping strip of ribbon through both brass loops 15 and 19 down in and over upper free edge of loop 19 through the edges hanging ready to connect with third brass loop 17 to corset loop extending up and out from the corset center back. Snapping again each to its own strap snapper.

The right strap U snaps over end of third brass loop 17 on corset's center back snapping to its own strap by adjusting snapper. Left strap end V snaps over the third brass loop 17 to its own strap end. This can be attached on and off at will to no inconvenience to the wearer.

While the brassière can be made and marketed as a completed unit, one important application of the unit, is that the pliable wire and copper connector can be made in all sizes and type. Minus any cost for machinery or middleman. With one's bare hands if necessary. When one's got the correct convex measure of the bosom's edge.

Fitting regular and small sizes. Taking in hand also exceptional sizes, like very small, large, altogether large, huge and pendulous. Aligning all bosoms and taking care of uplift by copper division. One needs no material whatsoever under cups. Up to the connector itself doing away with so much excess waste. Nonsense actually that serves no purpose except a little more bulk.

55 In use the arcuate braces B rest against the bosom's concavity or chest to which bosoms attached, securely, and tightly, immediately below the breasts. And are yieldingly held in place by a connector of copper S covered by plush attached to which are circular cups. The cups are therefore adequate to support and conforming themselves to the natural rotundity of the bosom without pressure or discomfort or injury to the soft and fine tissues of the breast.

60 In use the two wires and connector are inherently kept on a common plane.

65 By a pair of backs-16. Shut by three individually placed brass loops developing same by attachments of first taffeta double shaped and 70 elastic turned back over brass loop 15 at right center back over left brass loop left center back travelling to third brass loop on corset center back 17 brass loop. Sewing all of taffeta on to inside outer edges at side of each side of bosom.

75 With overhand stitching. But can be used ap-

plicable with machines in anyway at all. Attached to which then attaching elastic to outer edges of taffeta covering over, raw elastic edges by slipping in brass loops. Two on each side of back. Using same as two parts of closing.

Then attaching a third loop on corset to close designated itself out in the back on a woman's corset. By means of straps that are snapped each to its own. Around one outer edge by a corset loop. Like the companion form the present embodiment may be built into the garment as sold, or it may be applied to the ultimate consumer as a separate attachment.

As many changes could be made in the above article and many apparently widely different classically though holding to the general idea, the drawings should be looked at in an illustrative sense showing the limitless ideas that can be adopted from same brassiere.

Having thus described my invention, what I claim as new and desire to secure by the Letters Patent of the United States is:

1. In a brassiere, a body having spaced pockets, bands secured to side portions of each pocket, connecting members secured to the free ends of said bands, a brace comprising a single length of relatively stiff wire completely encompassing each of said bust pockets and secured thereto, bridge means interposed between said pockets and joining said brace wires, strap members connected at one end thereof to the top portion of each pocket and provided with adjustable fastening means on the opposed ends thereof, said strap slidably extending through said connecting members, said fastening means adapted to engage cooperating fastening means on a girdle thereby to exert a downward tension on said straps and an uplift on said pockets.

2. A brassiere as set forth in claim 1 wherein the connecting members are rings through which

30 said strap members extend diagonally of each other.

3. In a brassiere, a pair of conical cups each comprising a single piece of fabric of circular 5 outline, each cup divided into upper and lower halves, the upper half being on the bias and the lower half on the straight of the fabric, reinforcing means in the lower outer side portion of each cup, said reinforcing means comprising a 10 triangular dart extending from the outer edge of each cup to the apex thereof, a supporting brace comprising a single length of relatively stiff wire encompassing each of said cups and secured to the periphery thereof and a connector joining 15 and spacing said brace wires, and means secured to outer edges of said cups for supporting the brassiere about the body of the wearer.

4. In a breast supporting garment comprising 20 a pair of flexible breast cups, means secured to outer side edges of said cups for supporting the garment upon the body of the wearer, a supporting frame comprising a pair of breast encircling wire members secured to the peripheries of said cups, a yieldable connector joining and spacing 25 said members, each of said wire members having interlooped ends forming coupling means, said connector having an arcuate central portion and inwardly directed sleeve means receiving and housing the interlooped ends of said members.

30 GERTRUDE WHITMAN.
